UNITED STATES PATENT OFFICE.

EDWARD F. RYMAN AND EDWARD W. STEVENSON, OF WILKESBARRE, PENNSYLVANIA; SAID STEVENSON ASSIGNOR TO SAID RYMAN.

RAILWAY-SIGNAL.

SPECIFICATION forming part of Letters Patent No. 758,855, dated May 3, 1904.

Application filed October 19, 1903. Serial No. 177,548. (No model.)

To all whom it may concern:

Be it known that we, EDWARD F. RYMAN and EDWARD W. STEVENSON, both citizens of the United States, and residents of Wilkes-
5 barre, in the county of Luzerne and State of Pennsylvania, have invented certain new and useful Improvements in Railway-Signals, of which the following is a specification.

Our invention relates to electric railway
10 signaling devices.

It relates specifically to signaling devices in which by means of apparatus situated in the engineer's cab a record is made of the fact that he has passed a danger-signal and has
15 either taken notice thereof or has disregarded the warning.

In the drawings annexed hereto and forming a part of the present specification, Figure 1 shows diagrammatically how the device is
20 attached to the locomotive and the general arrangement of parts; Fig. 2, a diagram of the essential electrical and mechanical appliances for operating the same; Fig. 3, an elevation of the buffer located adjacent to one rail or
25 between the two when the signal is at "danger;" Fig. 4, an elevation of the buffer when the same is set at "safety," and Fig. 5 a plan view of the buffer.

Referring to the drawings, A is the locomotive-body, B the pony-wheels of the locomotive, and C the bearing-box of the pony-wheels, to which the contact-shoe and some of its accessories are attached.

D is the shoe, pivoted at E, regulated as to
35 height of travel by the adjusting device F and adapted to be operated by the buffer G. The buffer G is so arranged in reference to the path of travel of the shoe D that when the vertically-moving portion H of the buffer G
40 contacts with the shoe D the engineer is notified that the semaphore ahead is set at "danger." The position of the movable portion H of the buffer G is controlled by the semaphore-rod I through the intermediation of the link J. Controlled by the motion of the shoe D is the contact-rod K, which opens and closes the electric circuit L, located in the locomotive-cab. Operated by the movement of the rod K is a registering apparatus M, adapt-
45 ed to record the fact that the shoe D has 50 passed over the buffer G and announced the fact by ringing the bell N, lighting an electric light, or giving the signal in any of the well-known ways.

O represents pawls acting on the ratchet-wheel P to operate the register M, although any well-known ways of operating the register may be employed.

Coöperating with the shoe D and the parts previously mentioned is the lever system Q, 60 which is under the control of the engineer. The shoe D carries a notched projection R, which engages with a notched portion of the lever system and under ordinary running conditions engages one of the upper notches 65 of the projection R, as shown in Fig. 1. Actuated by and under the control of the lever system Q is a register or indicator S, operated by the lever system Q through the intermediation of the pawls T.

The operation of our device is as follows: When the track is clear, the shoe D passes freely over the buffer in the normal position. (Shown in Fig. 4.) Should, however, the semaphore-signal be set to indicate "danger," the 75 rod I would be pushed inwardly and operating through the link J would elevate the upwardly-movable part to the position shown in Fig. 3. When under these conditions a locomotive came within the danger zone, the shoe 80 D would impinge on the buffer H, would force up the rod K, close the electric circuit L, ring the bell N, light a lamp, blow a whistle, or give any of the well-known signals that are plain to those skilled in the art. As the rod 85 K rises it would through the pawls O actuate the register M and make a record of the fact that a danger-signal had been passed. The electric circuit being closed would continue to notify the engineer of the fact until he by operating the lever system Q allowed the shoe 90 to fall to its normal condition—i. e., to its position when the buffers were in the position shown in Fig. 4; but in doing this the pawls T, acting on the register S, would record the 95 fact that he had released the danger-signal. The two registers, therefore, M and S, would form a record of two facts—viz., that a dan-

ger-signal had been passed and that the engineer had observed the first and released the alarm.

In order that the effect of the blow of the shoe D striking the buffer G may be minimized, we have arranged a compensating device U, which may be springs, compressed air, or any other well-known means for lessening an abrupt blow.

10 Having thus fully described and illustrated our invention, what we claim is—

1. In a railway signaling device, the combination of an upwardly-projecting, vertically-acting apparatus located in the line of motion 15 of the locomotive, a locomotive-truck, an automatically-actuated contact-shoe supported by the locomotive, an electric-circuit closer operated by said shoe, an electric register of the action of the said shoe, and a manually- 20 operated registering device controlling the

action of said shoe and signaling device, substantially as set forth.

2. In a railway signaling device, the combination of a vertically-moving buffer located in the line of travel of the locomotive, a shoe attached to the locomotive and adapted to be actuated by said buffer, a registering electric signal operated by said shoe, and a manually-controlled registering apparatus for supporting and releasing said shoe, and means for 25 lessening the impact of said shoe against the buffer, substantially as set forth.

Signed at Wilkesbarre, in the county of Luzerne and State of Pennsylvania, this 6th day of October, A. D. 1903.

EDWARD F. RYMAN.

EDWARD W. STEVENSON.
